UNITED STATES PATENT OFFICE.

SYDNEY STUART, OF LEICHHARDT, NEAR SYDNEY, NEW SOUTH WALES, AUSTRALIA,
ASSIGNOR TO JOHN HEINE & SON LIMITED, OF LEICHHARDT, NEAR SYDNEY,
AUSTRALIA, A COMPANY OF NEW SOUTH WALES.

AUTOMATIC CAN-BODY-MAKING MACHINE.

Application filed October 11, 1924. Serial No. 743,002.

To all whom it may concern:

Be it known that I, SYDNEY STUART, subject of the King of Great Britain and Ireland, residing at Allen Street, Leichhardt, 5 near Sydney, New South Wales, Australia, have invented new and useful Improvements in Automatic Can-Body-Making Machines, of which the following is a specification.

This invention relates to can body making machines in which sheet metal blanks are drawn from a stack, and advanced along the bed intermittently, and at the dwells in the movement are respectively notched and edge folded ready for the closing operation, and 10 are thereafter moved on to a mandrel where the bodies are "formed" and the open folded edges are engaged and the seam thus produced closed by the operation of a hammer press.

20 Machines of this type are capable of being operated only at a limited rate of output, and though it is generally recognized that it is highly desirable to increase their capacity, no means have been conceived heretofore whereby their output rate can be substantially increased.

The object of the present invention is to provide a can body making machine utilizing elements of known machines of the 30 type above indicated but having an output capacity at approximately twice that of the known machines running at the same speed, notwithstanding that the corner notching, edge folding, forming and seam closing operations are as heretofore carried out on a single bed and mandrel, and the speed of operation of the machine elements is maintained at the present rate.

40 The invention consists in extending the machine bench or bed and the mandrel, and in operating simultaneously on a train of blanks on the same bed and on the same mandrel, advancing the train step by step, and notching, folding, forming and closing a plurality of blanks simultaneously in each stroke of the machine.

45 The sheet blanks are detached by pneumatic or other known devices from the bottoms of stacks of blanks which are disposed in serial order over the starting end of the machine bed. Two, or it may be more than two blanks, so detached from their respec-

tive stacks are delivered onto the bed and slid forwardly simultaneously along it by a reciprocating feeder, each blank disposed 55 a certain distance thereon behind the preceding blank in order. The blanks are moved forward step by step, and during the dwells at certain stations are successively operated on by mechanism of a known type at 60 which respectively their corners are notched, their lateral edges are open folded, and they are "formed" to cylindrical shape and the folded edges engaged and seamed, two or 65 more of the blanks being thus operated on simultaneously in each operation. The hammer press then closes the seams, the mandrel being meantime supported against the hammer blow by packing wedges which are set appropriately by automatic mechanism between the mandrel and the machine frame 70 to form an abutment for the mandrel. At the completion of the seam closing operation the bodies are moved forwardly along the mandrel on to the usual conveyor mechanism which brings them to the side seam 75 soldering assembly.

In each stroke of the mechanism a plurality of bodies—usually two—is thus produced simultaneously. A high rate of production without speeding up the machine operations is thus obtained, with practically no increase in the cost of supervision, and negligible increase only in cost of operation.

80 In the accompanying explanatory drawings:—

Fig. 1^a (which is a continuation of Fig. 1), 85 is a longitudinal sectional elevation showing the essential portions of a cylindrical can body making machine according to the present invention;

Fig. 2 is an elevation at the feed end of the machine;

Fig. 3 is a transverse section on the plane 90 3—3 Fig. 1^a;

Fig. 4 is a fragmentary side elevation on enlarged scale of portion of the structure at the mandrel position;

Fig. 5 is a transverse section on the line 100 5—5 Fig. 4, showing the mechanism with a blank sheet advanced and resting on the mandrel with the forming-wings by which the blank is folded round the mandrel shown in their upper positions;

Fig. 6 is a fragmentary elevational section (on enlarged scale) detailing one of the locating pawls by which the sheets are positioned in endwise register on the mandrel;

5 Fig. 7 is a transverse section on the plane 7—7 Fig. 4;

Fig. 8 is a plan view of a sheet blank notched at the corners;

10 Fig. 9 is a transverse section through a sheet blank with the lateral edges open folded for engagement by interlocking together to form the body side seam; the folding being effected after the notching illustrated in Fig. 8;

15 Fig. 10 is a fragmentary section showing the interlocking of the lateral edge folds of the blanks (Fig. 9) to form the body side seam;

20 Fig. 11 is a diagrammatic view explanatory of the progressive movement of blanks from stage to stage in the several operations of the machine, and indicating the operative stations at which the blanks are operated or in pairs; and

25 Fig. 12 is a fragmentary detail illustrating the action of the locating pawls.

It is important to note that the feed operates in such a way that though each sheet at each movement receives a two stage advance forwardly, the sheets from the respective stacks are, after the first few strokes of the machine, disposed as a continuous train of blanks along the machine bed with intervening clearance spaces. At the notching 30 station in the machine illustrated which is designed for operating on two blanks simultaneously, two blanks, one from each of the two stacks, are located adjacently on the bench and are notched simultaneously. 35 These two blanks are thereafter advanced step by step along the bed to the folding station, and thereafter to the forming station where they are formed simultaneously, and then to the closing station where they are closed simultaneously. The closed bodies finally pass from the seam closing mandrel on to the carrier mandrel, along which they are moved by a picking arm and by a claw chain feeder, the closed seams successively 40 passing over a fluxing roller and a soldering iron. The soldering or the locked seams is effected in an operation independent of and subsequent to the completion of the closing operation. The machine bed is fitted 45 with a fence 13 along either side of it. The sheets are kept in alignment by these fences.

To facilitate explanation of the operation of the machine, it is desirable to refer firstly to the diagram, Fig. 11; this diagram shows 50 the positions of the blanks at each successive stage of the feed movement, that is at each stroke of the machine. The blanks taken from the first blank stack O are designated A, A', A², A³, A⁴, A⁵; the blanks taken from the second blank stack O' which is in ad-

vance of the first blank stack are marked B, B', B², B³, B⁴, B⁵. The stroke of the feed device is such that in each movement the respective blanks are moved ahead along the bench through a distance more than 70 double the length of one blank. The positions of the train of blanks at the completion of successive strokes of the feeder are shown on the lines marked respectively, C,

75 D, E, F, G, H, J, and K. In the C position, at the starting of the machine, before any blanks are slid out from the stacks, A and B indicate respectively the lowermost sheet in each of the two stacks, these sheets being

80 shown bowed to bring them into the range of the feeder. O represents the first blank stack position, O' the second blank stack position, L and L' the "stations" at which the corners of the blanks are notched, M and M'

85 the "stations" at which the longitudinal edges of the notched blanks are folded, and N and N' the "stations" at which the folded edge blanks are closed by the press hammer.

Starting from the position C, the blanks A and B at the bottom of the respective stacks 90 O and O' are taken by the feeder in the manner hereinafter described and moved forward two stages; these blanks are thus brought to the positions marked A and B respectively on the line D. At the next

95 stroke of the feeder, two more blanks A' and B' are taken from the stacks O and O' and moved on two stages, whilst the previously extracted blanks A and B are at the

100 same time moved on two further stages, so that now the four blanks A, B, A' and B' occupy the respective positions shown in line E, with the blank B in the notching position L'. In the movement of the feeder at position E, the sheets A² and B² are taken from the respective stacks O and O' and together with the sheets A, A', B, B' are moved forwardly two stages, bringing them to the positions shown on the line F, with B at the

105 folding station M, and B' and A at the notching stations L' and L. There are thus at this stage six blank sheets on the machine bed. In the next feed movement, sheets A³ and B³ are taken from the first and second

110 stacks O and O' respectively, and, as before, these sheets, together with the sheets previously taken, are all moved forward two stages, the resulting position of the eight

115 blanks being shown in the line G. In this position, B' is located at the folding station M, and B² and A' at the notching stations L' and L respectively, where they are simultaneously notched. Thence a similar move-

120 ment advances all the sheets, including the sheets A⁴ and B⁴, from the blank stacks, bringing the position of the sheets on the bed as shown at line H. At this stage the sheet B has reached the forming and closing

125 station N, the sheets A and B² have reached the folding stations M' and M, and the

130

sheets B^3 and A^2 have reached the notching stations L' and L . At the next forward movement of the feeder bars, represented on the line J , the formed body B passes on by the conveyor mechanism to the soldering assembly, and its place at station N is taken by sheet B' . The next movement of the feeder bars moves the body B' on to the conveyor, and moves sheets A and B^2 together to the forming and closing stations, and so on through subsequent movements. When a sufficient number of feeder movements have been thus made, the operating stations are in order charged with blanks, and these blanks are operated on at those stations during the dwells in the step-by-step feed motions for notching (stations L and L'), edge folding (stations M and M') and forming and closing (stations N and N'). In the early strokes of the machine, one sheet only reaches the operating stations, but when these early strokes of the machine have been completed, two blanks in train order reach the stations simultaneously at each stroke and these two blanks are at each station operated on simultaneously.

In Figs. 1 and 2 of the drawings, blanks are shown on the machine bed, and their positions, shown diagrammatically in Fig. 11, are correspondingly referenced, O representing the first stack of blanks, O' the second stack of blanks, L and L' , the notching stations, M and M' the folding stations, and N and N' the forming and closing stations. At these latter stations the seam folds are engaged by the jaw action and they are closed by means of the press hammer acting under the anvil mandrel.

The stack casing 20 carries the first stack 40 of blanks O , and the casing 21 the second stack of blanks O' ; these casings are each constituted of a front plate 22 supported over the bed 12 of the machine, a cheek plate 24 at each side, and a back plate 25 which is adjustably carried on the cheek plates 24 by means of a bridge fitting 26.

The bottom end of each of the back plates 25 is bent outwardly as shown at 27 to offer a fair lead for the delivery of the metal sheets from the stacks in single file. The back plates 25 need not be of any considerable width. As shown in Fig. 2, they consist only of relatively narrow bars, their only function being to hold the stack of metal sheets compactly and to permit single sheets, when released successively from the bottom of the stacks, to be passed out and pushed along the machine bed. The stacks of metal sheets in the stack casings are supported on lips or shelves 28 projecting forwardly from the carriers 23 and located near the cheek plates 24; these shelves support the sheets only under their lateral edges. The sheets are thus entirely unsupported intermediate the shelves 28 except by their own stiffness, and they

may therefore be bent down centrally whilst still remaining supported on the shelves under their lateral edges. They are bent one by one at each stack simultaneously by means of a pneumatic device comprising a tubular plunger 29 having two branch pipes 30 projecting from it fore and aft with sucker mouths fitted on the ends of these pipes. The sucker mouths are directed respectively towards the bottoms of the two stacks. The plunger 29 is connected at the bottom end to an exhaust pump through a flexible pipe 31, 32 being a three-way cock for controlling the air flow. Cocks 130 and 131 are fitted in the branch pipes 30. When all these cocks are open, the machine will operate as a double action machine, that is to say, it will feed blanks in pairs and operate on them in pairs to form two bodies simultaneously, but if either 130 or 131 be closed the other will 70 continue to operate and the machine will then operate as a single action machine. If the cock 32 be opened to atmosphere the take-off will be rendered inoperative. The plunger 29 carries an offset tappet roller 33 which works in a cam groove 34 in a disc 35 which is rotated in timing with the feeder by chain gearing engaging the sprocket wheel 36 on the end of the shaft on which the disc 35 is keyed. The plunger may be 80 fitted with an automatic valve arranged to open only when the plunger is in the upper position, but in practice it is not thought necessary to use such a valve as the waste resulting from the continuance of the indraft of air during the time the plunger is in its lower position is not material. When the plunger 29 makes an upward movement, the sucker mouths 35 are simultaneously brought 85 up against the underside of the bottom sheets in the stacks O and O' respectively. In the downward movement of the plunger, the suckage thus caused to operate on the underneath sheet in each stack flexes that sheet and brings it to the bowed position shown in 90 Fig. 2, its lateral edges being still sustained on the shelves 28. When the sheets are thus bowed down their middle parts are engageable by the push claws 36 on the offsets which are fixed on the feeder bars 37; these 95 push claws are formed with finger ends which take over the back edges of the down-bent sheets and so hold those sheets in down-bent position during the first forward feed 100 movement. They are mounted as pawls on pins 38, and in the retiring movement of the feeder they may kick free under any obstruction which they may meet and come back to the normal full back position which is shown 105 in Fig. 1, ready to engage with the next sheet which is brought down to the engageable position by the next action of the pneumatic plunger. 40 are pinching springs each constituted of a single leaf of spring steel 110 mounted as shown at 41 on each cheek plate. 115

- As the sheets taken from the stacks are pushed forwardly by the feeder bars they are caused to pass over the bed of the machine under the springs 40, these springs holding them down firmly on the bed during the retiring movement of the feeder bar 37, so that they come to an assured position at each movement, and remain there undisturbed until they are again subjected to the operation of the feeder bars.
- The feeder bars 37 are mounted on a slide head 43 which moves in guide ways 44 on the machine bed. The head 43 is reciprocated by means of a pitman or like mechanism 45, the wrist pin housing 46 of this pitman being preferably fixed in the slide socket 43 by a dove-tail stub 47 secured by a cotter key 48 and a pinching pin 49.
- The feeder bars 37 are armed with pawls at stage intervals along their length; these pawls are all spring pawls so that they depress to allow them to pass back under the advanced sheets and to spring up again and take behind blank sheets which have been moved forward in the previous feeder stroke. These several spring feeder pawls are respectively numbered 42, 42^x, 62, 63, 64, 65, 66, 67, and 68. At their rear ends the feeder bars 37 are connected at 95 to other feeder bars 96 located close together near the centre of the sheets and slidably housed in slots in the mandrel 70, as shown in Figs. 5 and 7. Spring feed pawls mounted on each of these bars 96 are respectively marked 69, 71, 72, 73, and 74.
- Above the bed at each side of it, is a rail 83, 84 being milled head screws for holding it lengthwise in relation to the bed. Each of these rails carries eight pawl boxes 85, 86, 86^x, 87, 185, 186, 186^x, and 187, which are adjustable along them by means of pinching screws 88. In each of the boxes 85 and 86^x a spring check pawl 89 is carried. In the operating movement of the feeder bars the blank sheets are pushed forward by the pawls 63 and 64 respectively, and pass under these pawls 89 which then snap back in behind the sheets which have so passed. In each of the boxes 86 and 87 a spring kick-back pawl 132 is carried. These kick-back pawls 132 have a limited movement which allows the sheets to pass under them in the operating movement of the feeder bar, but the springs which act on them are sufficiently stiff to cause each one of them to push the nearest blank sheet backward at the commencement of the retiring movement of the feeder bars, the feeder movement being regulated so that the sheets are slightly overfed. At each operative feeder bar movement the sheets are moved forward two stages. One sheet passes under the check pawls 89 in each of the boxes 85 and 86^x and under the kick-back pawl 132 in the box 86. Simultaneously the following sheet passes under the check pawl 89 in the box 85. The pawls 89 then snap back into their locating position. The sheets are pushed forward by the feeder bar pawls 63 and 64 until their forward ends press against the kick-back pawls 132. When the retiring movement of the feeder bar begins, the kick-back pawls 132 react and push back the sheets until their back edges abut against the associated check pawls 89; the sheets are thus positioned in register with the dies for the notching operation which is effected at this station (L—L').
- In the first forward movement of the feeder bar 37, a sheet is taken from the stack O and moved to the position Q, another sheet being taken simultaneously from the stack O' and moved to the position Q^x. Assuming that the machine has been in operation for sufficient time to bring the sequence of sheets correct, so that they reach the operative stations L, L', M, M', N, N', in pairs, as has been described in reference to Fig. 11, the sheets at the station L, L' are simultaneously notched by the dies 50, 51, 52, and 53, as shown in Fig. 8. These dies are fitted in housings 54 and are arranged on a crosshead which is connected by a link 55 to a bell crank 56 to which timed oscillation is imparted through a pitman 57 which is driven from an eccentric 58. The pitman 45 is driven by a crank pin 59, this crank pin being overhung on a disc 60 keyed to a shaft 61.
- When the blank sheets have been notched at the stations L and L', they pass on to the folding stations M and M' where their edges are folded over, as shown in Fig. 9. The pawl boxes 185, 186, 186^x, and 187 are mounted on the rails 83 and their associated pawls 89 and 132 operate to locate the blank sheets for the folding operation precisely in the same manner as the pawls which have just been described in connection with the registering of the sheets at the notching stations.
- 90, 91 and 92 are cylindrical housings each of which carries a spring presser 93 which bears down on the sheets as they pass beneath them and prevents the sheets from moving backwards in the retiring movement of the feeder bars. These pressers are located only at blank or inoperative stations, as it is not necessary to so accurately locate the sheets there as it is at operative stations.
- After the folding operation, the sheets are moved forward to the forming and closing stations N and N'. They are pushed forward by the pawls 68 and 69 on to a mandrel 70. Provision is made for locating the sheets in spaced order and squarely in register across the mandrel 70; the means for doing this comprise kick-back pawls 98

acted on by springs 99 carried in adjustable jaw pieces 99* held by clamping screws 100* and by adjustable back checks 100. These pawls 98 function in the same manner as the pawls 132 previously described in connection with the notching and folding operations. The checks 100 are formed angularly as shown at 101 on their top portions in order that the forwardly moving sheets may vault them, and guide lips 102 are fixed above them so as to leave clearance spaces through which the sheets may be fed forward. In the final feed movement (see Fig. 7) the sheets which have been edge folded, as shown in Fig. 9, at the stations M—M', are flexed upward at their lateral edges in vaulting over the top portions 101 of the back checks 100. As soon as the back edges of the sheets pass over the checks 100 they snap down to straight position, as shown by dotted lines in Fig. 7, and the checks 100 then prevent these sheets from being moved backward. In the forward feed motion, the front ends of the sheets are brought up against the kick-back pawls 98. In the feed movement these pawls move a little, compressing their springs 99, but immediately the feed movement reverses, the springs 99 re-act and cause the pawls to push back the sheets until the back edges of the sheets come in square contact with the checks 100. The sheets being thus located on the mandrel are immediately gripped and held on the mandrel by the anvil wedges 103 and 104; the lowermost of these wedges 104 is loosely supported at either end by a carrier ring 105 maintained by a spring 106, and it is anchored endwise by a cross pin 130 in a slotted hole; the springs acting through the rings 105 lift the wedge 104 when the upper wedge 103 is retired, so as to offer clearance for the feed movement of the sheets on to the mandrel 70, and they flex when the upper wedge 103 is forced inward by the lever mechanism 107. When the wedge 103 is forced in over the wedge 104, a sound abutment against the frame 108 is provided to support the mandrel 70 whilst the seam is being closed by the blow of the press hammer 109. When the sheets are thus gripped by the wedge 104 on the mandrel 70 and before the hammer 109 is brought up to close the seam 110 (Fig. 10), the sheets are bent around the mandrel by the forming jaws 119—120 to "form" the bodies. 111 are lateral fences flanking the back checks 100 and functioning to set the sheets centrally across the mandrel. As the sheets are fed forward over the checks 100 and between the fences 111 their edges are received on support platforms 112 which are pivotally carried on centres 113; these platforms are movable radially, being attached to arms 114 which are linked connected at 115 to timed operating mechanism which withdraws them radially outward after the sheets have been gripped by the wedges 103—104 on to the mandrel 70 and are thus securely held. When the platforms 112 are thus retired, clearance is offered for the downbending of the sheets; this downbending brings the folded side edges 116 and 117 (Fig. 9) of the sheets into engagement under the hard inset piece 118 in the bottom of the mandrel 70 to take the blow of the press hammer 109. The infolding is effected by means of forming jaws 119—120; these jaws being respectively pivotally carried on crossed centres 121 and 122 and actuated by linkages 123 and 124. This device for effecting the infolding of the sheets under the mandrel is not novel, and no claim is made in respect of it. Some features of the machine of a structural character which are well known in the existing practice of the art are not described, the present description including only sufficient of the known practice to make the novelties, in which the present invention consists, completely understood.

After the bodies have been closed on the mandrel 70 they are fed by the pawls 71—72—73 and 74 on to the carrier mandrel 75 along which the closed bodies 76 are moved until the most forward one is engaged by a finger claw 79 on the drag chain 78. The next following body is engaged by a pawl 82 on the side of the oscillating feed arm 77 and thereby brought in turn under the drag chain 78, the following finger claw 79 of which engages it and moves it along the mandrel 75. The chain feed so moves the bodies in train order with their closed seams in contact with the fluxing wheel 80 and thereafter into contact with the soldering iron 81. The fluxing and soldering assembly shown in the left hand portion of Fig. 1^a contains no novel features, and fluxing and soldering assemblies otherwise arranged may be used in its place.

In practice it is not probable that the machine would be extended so as to make it usable for the manufacture of bodies three at a time, or four at a time. There is a practical limit determined by the balance of convenience to the number of body closing operations which might be conducted simultaneously according to the method of the invention. Clearly, it would be undesirable to extend the machine so that it would be usable for the making of more than two bodies when those bodies are of any considerable length. It might, however, be adapted for the making of more than two bodies when the body lengths are relatively short. It is accordingly to be understood that the at-

6
tached drawings disclose an embodiment of the invention for a duplex machine, but that in favorable circumstances the structure may be adapted for a machine arranged for the 5 making of bodies in threes or fours simultaneously, on the same principle.

The pneumatic arrangement which has been described which functions to suck down the lowermost sheet in each stack of sheets 10 so as to bring it to engageable position at the centre part of it with the push claws 36 would be preferred in practice, but there are mechanical devices known in the art for detaching the lowermost sheet of a stack so 15 that it may be then engaged by a reciprocating feeder operating below the stack. Any known form of bottom sheet extractor mechanism might be used in substitution for the pneumatic device which has been de- 20 scribed for that purpose.

What I claim as my invention and desire to secure by Letters Patent is:—

1. A can body making machine comprising a plurality of open bottom stack casings 25 disposed in serial order over the machine bed, each of said stack casings being adapted for carrying a tier of sheet metal blanks, means disposed below said stack casings for simultaneously detaching the bottom sheet 30 of each tier in successive operations, corner notching dies adapted for simultaneously notching a plurality of adjacent sheets, edge folding devices adapted for simultaneously folding the sides of adjacent sheets, body 35 forming devices, a closing hammer, an anvil mandrel and supporting abutment adapted for forming and closing a plurality of can bodies simultaneously, a reciprocating pusher feeder adapted for advancing the sheets 40 step by step in train order along the machine bed and bringing them to a condition of rest in groups at each operating station, means for adjusting the position of the sheets at

each operating station, a carrier mandrel, 45 means for delivering a plurality of closed can bodies on to said carrier mandrel and means for imparting timed movements to the sheet detaching means, the feeder, the notching dies, the edge folding devices, the forming devices, the anvil abutment, the 50 closing hammer, and the closed can delivery means.

2. In a can body making machine according to claim 1, means for adjusting the positions of the sheets on the anvil mandrel 55 preparatory to forming and closing, said means including lateral fences and pivoted platforms insetting below said fences to support the lateral edges of the sheets and means for retiring said platforms after the sheets 60 have been gripped on the anvil mandrel in the forming operation.

3. In a can body making machine according to claim 1, means for adjusting the positions of a plurality of sheets on the anvil 65 mandrel, said means including lip guides and stationary back checks, said checks having angular heads adapted to flex the lateral edges of the sheets upward in the feeding movement and to prevent the sheets from 70 moving backward in the reverse movement of the feeder, and spring kick-back pawls at the forward ends of the sheets.

4. A can body making machine comprising a plurality of blank stack casings, corner notching dies, and edge folders serially arranged, a forming mandrel and closing press assembly, and a reciprocating feeder 75 adapted for simultaneously delivering in each stroke of said feeder a plurality of blank sheets at each respective operating station and a plurality of formed bodies on to a carrier mandrel.

In testimony whereof I affix my signature.

SYDNEY STUART.
